UNITED STATES PATENT OFFICE.

WILLIAM T. SHERMAN PATE, OF INDIANAPOLIS, INDIANA.

MORTISING-MACHINE.

1,397,900.

Specification of Letters Patent.

Patented Nov. 22, 1921.

Application filed November 18, 1920. Serial No. 424,948.

To all whom it may concern:

Be it known that I, WILLIAM T. SHERMAN PATE, a citizen of the United States, and a resident of Indianapolis, in the county of Marion and State of Indiana, have invented certain new and useful Improvements in Mortising-Machines, of which the following is a specification.

My invention relates to improvements in wood working machinery, and it consists in the constructions, combinations, and mode of operation herein described and claimed.

One of the foremost objects of the invention is to provide a mortising machine for cutting the bolt slot and rebate in objects such as furniture drawers and the like.

A further object of the invention is to provide a mortising machine by means of which an elongated cavity may be bored, with a surrounding relatively shallow depression or rebate, the idea being to provide a place into which either a lock, guard plate, or the like, is to be set.

A further object of the invention is to provide a machine of the class described, wherein the work may be clamped in position and the foregoing operations performed without doing more than merely shifting the proper levers and not requiring the removal of the work for a changing of position or the performance of other operations in respect thereto.

Other objects and advantages will appear in the following specification, reference being had to the accompanying drawings, in which:

Figure 1 is a vertical section of the improved mortising machine, showing the levers thrown back to project the small bit for cutting the deep mortise.

Fig. 2 is a detail sectional view showing the lever thrown forwardly to retract the small bit and extend the larger for cutting the shallow recess or rebate.

Fig. 3 is a horizontal section showing how the work carriage is moved to one side to cut the mortise as the small bit is rotated.

Fig. 4 is a similar view showing how the work carriage is moved to the other side in cutting the rebate.

Fig. 5 is a detail side elevation illustrating how the work is clamped on the work carriage.

Fig. 6 is a front elevation of the machine,

Fig. 7 is a detail enlarged sectional view 55 of the improved double bit,

Fig. 8 is a cross section on the line 8—8 of Fig. 7,

Fig. 9 is a cross section on the line 9—9 of Fig. 7, and

Fig. 10 is a detail perspective view illustrating a part of a piece of work mortised and rebated by this machine.

In order that the reader may quickly obtain a general idea of the purpose and 65 mode of operation of the mortising machine, the description of the details is here preceded by a brief sketch. The work W is secured on the carriage 1 by the eccentric clamps 2. The lever 3, which moves the carriage 1 back and forth, is at this time in the left hand position.

The boring lever 4 is moved backwardly into the position shown in Fig. 1, which act extends the small bit 5 and causes it to bore 75 into the edge of the work W. The operator now shifts the work lever 3 toward the right, as in Fig. 3, causing the bit 5 to form the mortise M.

Now pull the bolt lever 4 forwardly. The 80 large or secondary bit 6 is now projected while the primary or smaller bit 5 is retracted within the secondary bit, causing engagement with the edge of the work as shown in Fig. 4. The operator now pushes 85 the work lever 3 toward the left, causing the cutting of the rebate R so that when the work W is removed from the machine, the edge has the appearance illustrated in Fig. 10. The mortise and rebate are cut for such 90 purposes as providing a place for a lock, or inserting the face plate through which the bolt of a lock is to project into the mortise. This gives a general idea of the purpose and mode of operation of the machine, 95 attention now being directed to the details.

The frame 7 is of any desired construction. It includes guide ribs 8 on which the work holder bracket 9 is vertically movable. Adjustments of the holder are made by turning the handle 10 of the screw 11 which is threaded into the follower 12 of the holder bracket. The lower end of the screw has a swivel mounting 13 on the base of the frame.

A belt 13, applied to the pulleys 14 and 15 105 drives the primary and secondary bits which can be extended and retracted as the case may be, while rotating at the requisite

speed. An extension 16 provides a mounting for the pivot 17 of the boring lever 4, the bifurcated end of this lever fitting over pins 18 of a head 19, which is by this means slid 5 back and forth to shift the bits.

There is a guide rod 20 running from the head 19 on the front to a cross head 21 at the rear. The guide rod slides in the upper part 10 of the frame. The crosshead embraces the spindle 22 of the bits, the end collars 23 causing the spindle to slide back and forth with the crosshead, still permitting the free 15 rotation of the spindle as is obviously necessary.

15 A bracket 24 supports a pair of levers 25, the lower ends of which are bifurcated to straddle the pins 26 of the slide bars 27, the upper ends being arcuately slotted to receive the pins 28 of the cross head. The shifting 20 of the boring lever 4 produces a differential motion between the crosshead and levers 25, of an extent equal to the length of the slots in the links.

Forward motion, for example, of the boring 25 lever 4, causes the guide rod 20, crosshead 21 and pins 28 to move backwardly, all the while retracting the primary bit 5 through the connection of the crosshead with the spindle 22, until the right ends of 30 the slots are reached by the pins 28, at which time, continued forward motion of the boring lever 4 causes the levers 25 to rock and shifts the slide bars 27 forwardly carrying the larger and secondary bit 6 with it. On 35 the reverse motion of the boring lever the action is the same. The pins then being at the right end of the slots will slightly retard the retraction of the secondary bit 6, but when this retraction starts, as when the pins 40 28 reach the left end of the slots the primary bit 5 will not yet have been projected so that the secondary bit will have time to clear the work before the former bit enters.

Consider now the construction of the primary and secondary bits. The slide bars 27 carry a bearing 29 at the front end, in which bearing the secondary bit 6 is rotatably mounted. The spindle 22, journaled in a bushing 30 on the main frame, has a non-circular extension 31 which finally merges into the primary bit 5. The sleeve 32 of the bit 6 includes an annular collar 33 which occupies a corresponding recess in the bearing 29, for the purpose of preventing axial movement 45 of the secondary bit but still enabling the rotation thereof through the non-circular part 31 of the continuously revolving spindle 22.

When the boring lever 4 is shifted in the 60 manner explained above, the spindle 22 with its non-circular extension 31 and primary bit 5 moves axially as a whole, but this motion is relative to the secondary bit 6 in which the primary bit slides. It is not until 65 the pins 28 reach the back of the slots in the

levers 25 that the bit 6 begins to move oppositely to the bit 5, and that movement is produced through the slide bars 27, etc.

The work carriage 1 slides laterally in ribs 34 on the work holder bracket 9, this movement being produced through the connection of the work lever 3 to the carriage at the lug 35. The latch 36 of the work lever engages the various notches in the quadrant 37 to hold the work carriage in extreme or intermediate positions, but obviously when the button 38 of the latch is depressed, the lever may be worked back and forth freely so as to correspondingly slide the carriage. 80

Rectangular straps 39 slide vertically in guides 40 on the work carriage 1 when the eccentrics 2, which occupy the openings in the straps, are rotated through the crank and link connections 41 of the clamp lever 42. 85 The work W is laid upon the straps 39 and when the clamp lever 42 is pulled forwardly, the eccentrics 2 raise the straps 39 and work W against the stationary clamp shoes 43 so that the work is firmly affixed to the carriage for the subsequent operation of forming the mortise and rebate. 90

Adjustments of the clamp shoes 43 can be made at 44 on the standards or rods 45 on which they are mounted. These rods or standards are carried by the work carriage as clearly shown in Fig. 1. When it is desired to bore a keyhole opening in the work simultaneously with the rebating operation, a bit 46 is inserted in the holder 47 which is vertically slidable in the head 48 of the extension 15. This holder is revolved continuously by the belt 49 applied to the pulley 50, and moves up and down as the boring lever 4 is shifted back and forth, through the slide 100 links 51 which are pivoted between parts of the lever and the saddle 52. When it is desired not to bore holes with the final rebating operation, the bit 46 is simply removed and the shifting operation of the boring lever 105 is performed without it.

While the construction and arrangement of the improved mortising machine as herein described and claimed, is that of a generally preferred form, obviously modifications and changes may be made without departing from the spirit of the invention or the scope of the claims. 115

I claim:—

1. A mortising machine, comprising mortise and rebate cutters, one telescoping on the other; and means for alternately projecting and retracting said cutters to and from an operative position by simultaneous opposite movements. 120

2. A mortising machine, comprising a mortising bit, a telescoping rebating bit, means for continuously rotating both bits, means enabling relative sliding movement between the bits while rotating, and means 125 130

for alternately moving the bits in respect to each other to project them into an operative position.

3. A mortising machine, comprising a mortising bit, a circumposed rebating bit, means for continuously rotating both bits, means enabling relative sliding movement of the bits while rotating, and means including a lever, for sliding the bits in opposite directions to each other, including a crosshead associated with the mortising bit, and link connections associated with the rebating bit arranged to move the mortising bit slightly before the rebating bit is started.

4. A mortising machine, comprising a mortising bit, with a spindle and crosshead; a rebating bit slideable on the mortising bit, with guides, and link connections to the crosshead; means for continuously rotating both bits, permitting sliding motion of the bits while rotating, and means, including a lever, connected to the crosshead movable in opposite directions to shift the bits and alternately advance them in turn to the operative position.

5. A mortising machine, comprising a mortising bit with a non-circular portion and a stem; a crosshead, in which the stem is revoluble, having a guide rod extending to a head, slide rods at the sides of the stem, with a bearing supporting a rebating bit on said non-circular portion; pivoted levers with pin and slot connections to the slide rods and crosshead, and a boring lever connected to the aforesaid head for shifting the guide rod and mortising bit in one direction, at the same time shifting the rebating bit through the connected links and slide bars in the other direction.

6. A mortising machine, comprising the combination of a mortising bit, a circumposed rebating bit, means for continuously rotating both, permitting axial sliding movement during rotation, a single lever with connections to both bits for alternately projecting them into the working position, a work carriage, and means for shifting it at right angles to the axis of the bits regardless of the position of the latter.

WILLIAM T. SHERMAN PATE.
